UNITED STATES PATENT OFFICE

EINAR GUSTAF EVALD HOGNER, OF STOCKHOLM, SWEDEN

MECHANICAL PENCIL

Application filed January 15, 1929. Serial No. 332,576.

This invention relates to mechanical pencils and more particularly to an improved step by step feeding mechanism for the lead or crayon in such pencils.

5 The chief object of the invention is to provide improved means of this kind in which the pusher is automatically released at the end of its advancing movement after a lead has been entirely pushed out or consumed and 10 after returning to its starting position is again brought into operative engagement with the step by step feeding mechanism.

The invention consists, chiefly, in a step by step feeding mechanism for the lead or 15 crayon, comprising a stationary and a slidable rack, means for reciprocating said slidable rack, a slide, pawls carried by said slide and normally engaging said racks, a pusher connected to the slide, a control-member for 20 said pawls movably journaled in said slide, and a stop adapted to operate said control-member in the lowermost position of the slide so as to release the pawls from engagement with the racks.

25 In the accompanying drawings one embodiment of my invention is shown.

Fig. 1 shows an improved pencil according to my invention, partly in longitudinal section.

30 Fig. 2 shows a portion of the pencil in longitudinal section at right angles to the section in Fig. 1.

Fig. 3 shows a portion of the pencil in the same longitudinal section as shown in Fig. 1, 35 to illustrate the position of the parts immediately after the pusher has been released.

Figs. 4 and 5 are cross-sections on a larger scale on the lines IV-IV and V-V in Fig. 1.

40 Fig. 6 is longitudinal section of a portion of the pencil illustrating a modified embodiment of the pawls and their control member.

Fig. 7 illustrates the position of the parts 45 shown in Fig. 6 immediately after the pusher has been released.

Referring now to Figs. 1 to 5 of the drawings 1 indicates an outer sleeve of well-known type for mechanical pencils. In this outer 50 sleeve 1 an inner sleeve 2 of semicircular cy-

lindrical shape is provided having a vertical series of teeth or a rack 3 cut in its inner wall. A second inner sleeve 4 of semicircular cylindric shape is also provided in the outer sleeve 1 and has likewise a vertical series of teeth or 55 a rack 5 cut in its inner side-wall. The sleeves 2 and 4 together form a cylinder and the racks 3 and 5 which only extend along a part of the length of the respective sleeves are placed diametrically opposite to each other 60 (Fig. 5). The sleeve 2 is detachably attached to the sleeve 1 by means of a bayonet joint comprising a pin 6 engaging a groove 7 while the sleeve 4 is slidable in the said outer sleeve 1 and thus also slidable in relation to the 65 sleeve 2.

The stationary inner sleeve 2 is provided at one end with a bottom 8, from which a tube 9 having an annular flange 10 extends upwards in the centre of the pencil. The tube 70 9 serves as a stop member for releasing the feed mechanism in its lowermost position. In its other end the sleeve 2 carries a cylindric stop or end member 11 secured to it by means of screws 8^a or the like. The slidable inner sleeve 4 has at its lower end a bottom 12 containing an opening, which fits on the tube 9 but cannot pass the flange 10. The upper end of the said sleeve 4 is formed with a projection 13 extending laterally and having 75 an annular flange 14 on its upper side. A screw 15 extends through a hole in the said projection 13 and is screwed into the stop or end member 11. The head of the screw 15 forms a stop for the sleeve 4 to check its upward movement. A spring 16 is provided between the bottoms 8 and 12 and presses the sleeve 4 upwards, thus causing the projection 13 normally to rest against the head of the 80 said screw 15. Longitudinal recesses 17 are made in the outer wall of the sleeve 4 to reduce its friction when it slides in the sleeve 1. On the annular flange 14 a holder 18 for 85

an eraser 19 is provided which is covered by a removable cap 20 rests upon the projection 13 by means of a shoulder. In the cylindric channel formed between the sleeves 2 and 4 a slide 21 is provided having a pusher 22 secured thereto. The said pusher is placed in the axis of the pencil and 90

100

is guided by the tube 9. The slide 21 has a recess or groove 23 extending through it and forming two longitudinal openings in the periphery thereof diametrically opposite to each other. In the said recess 23 two pawls 24 and 24^a rotatable on pins 25 are provided, said pawls projecting through the said opposite openings and engaging the racks 3 and 5, respectively. A pin 26 (Fig. 5) engaging a groove 27 in the inner wall of the sleeve 2 is provided on the outer side of the slide 21 to guide the latter in such manner that the pawls 24 and 24^a are always right in front of the racks 3 and 5. The pawls 24 and 24^a are connected by a spring 28 tending to withdraw them from their engagement with the racks 3 and 5. The inward movement of the pawls 24 and 24^a is limited by pins 29.

A control-member or rod 30 is slidably journaled in the slide 21 between the pawls 24 and 24^a. On the upper portion of the said control-member which projects above the slide 21 a collar 31 is fixed limiting the movement of the said control-member downwards in relation to the slide 21. The control member 30 is forked in its lower portion (Fig. 2) and the prongs thereof enclose the spring 28 and project downwards below the slide 21 on both sides of the pusher 22. The upper edges 30 of the said prongs are checked by shoulders 32 of the slide 21 when the control-member is moved upwards, the movement of the latter thus being limited upwards as well as downwards. Two springs 33 are secured to the control-member and engage the back sides of the pawls 24 and 24^a in the lowest position of the control-member to press them towards the racks 3 and 5 against the action of the spring 28. Immediately above the points in which the springs 33 engage the pawls 24 and 24^a in the said lowest position (Fig. 1) of the control-member 30 the said pawls are provided with steep noses or shoulders 34. A spiral spring 35 is provided between the slide 21 and the bottom 12 to press the said slide upwards in the direction from the point of the pencil. One or more spring-pressed buffers 36 may be provided in the projection 11 to receive the shock when the slide is returned 50 by the spring 35. The leads or crayons to be fed are contained in a suitable magazine 37, for instance, of the revolving type.

The device now described works as follows:

To feed the lead the cap 20 is pressed downwards pushing in its turn the sleeve 4 in the same direction until the bottom 12 is checked by the flange 10 or the projection 13 is stopped by the stop or end member 11 and the upper edges of the sleeves 1 and 2. The stroke of the sleeve 4 is substantially equal to the pitch of the racks 3 and 5. When the sleeve 4 is thus pushed downwards the slide 21 is also pushed downwards by the pawl 24^a engaging the rack 5. The pusher 22 which is secured to the said slide 21 is consequently

also pushed down the same distance and feeds in its turn the lead from the magazine 37 before it. At this movement the other pawl 24 drags over the adjacent tooth of the rack 3 compressing the corresponding spring 33 and is caused by the said spring to engage the next tooth after the advancing movement has been completed. The cap 20 is now released whereupon the spring 16 restores the sleeve 4 as well as the cap 20 to their starting positions. During this movement the slide 21 is kept in position in relation to the sleeve 2 by the pawl 24 engaging the rack 3 while the pawl 24^a drags over the rack 5 until it engages the next tooth when the return movement is finished. By pressing and releasing the cap 20 in this manner the lead before the pusher is fed successively until it has been entirely consumed. The slide 21 then reaches the lowest point of its path and the prongs of the forked portion of the control-member 30 are checked by the upper end of the tube 9. The control-member 30 is thereby pushed upwards in relation to the slide 21 until the two springs 33 pass the projections 34 on the pawls 24 and 24^a. The spring 28 now withdraws the pawls 24, 24^a from the racks 3 and 5 respectively, the different parts thereafter having the positions shown in Fig. 3. The slide 21 thus released is now restored by the spring 35 to its starting position in the uppermost portion of the pencil body. At the end of this movement the upper portion of the control-member 30 is checked by the projection 11 and the said control-member is pushed back in relation to the slide 21 so that the springs 33 pass by the projections 34 and again bring the pawls 24, 24^a to engage the racks 3 and 5. The control-member 30 is then kept in its normal position by springs 33 engaging the slanting or concave back sides of the pawls 24, 24^a below the projections 34. Now the feeding can be started again as described above.

In the modified embodiment shown in Figs. 6 and 7 a wedge-shaped portion 38 of the control-member 30 converging upwards in the direction from the point of the pencil is used for releasing the pawls 24, 24^a. When the prongs of the control-member 30 are checked by the tube 9 at the lowest end of the path of the slide 21 the wedge 38 is pressed upwards, thus pushing the lower ends of the pawls 24, 24^a apart. The upper portions of the said pawls are thereby withdrawn from their engagement with the racks 3 and 5 and release the slide 21 which is restored to its starting position by the spring 35 as described above.

To put the mechanism apart, for instance when the magazine 37 is to be filled the bayonet joint 6, 7 is opened and the sleeves 2 and 4 as well as the magazine are drawn out from the outer sleeve 1.

The magazine 37 may be of any suitable

construction and forms no part of this invention. The mechanism above described can, if desired, be used without any magazine whatever. In this latter case the leads are placed by hand before the pusher and then successively fed, as described.

5 What I claim is:

1. In a mechanical pencil, a step by step feeding mechanism for the lead or crayon, comprising a stationary and a slidable rack, means for reciprocating said slidable rack, a slide, pawls carried by said slide and normally engaging said racks, a pusher connected to the slide, a control-member for said pawls movably journaled in the slide, and a stop member adapted to operate said control-member in the lowermost position of the slide so as to release the pawls from engagement with the racks.
- 10 2. In a mechanical pencil, a step by step feeding mechanism for the lead or crayon, comprising a stationary and a slidable rack, means for reciprocating said slidable rack, a slide, pawls carried by said slide and normally engaging said racks, a pusher carried by said slide, a control member for said pawls movably journaled in the slide, a stop member adapted to operate said control member in the lowermost position of the slide so as to 15 release the pawls from engagement with the racks, and a spring for returning the slide to its uppermost position.
- 20 3. In a mechanical pencil, a step by step feeding mechanism for the lead or crayon, comprising a stationary and a slidable rack, means for reciprocating said slidable rack, a slide, pawls carried by said slide and normally engaging said racks, a pusher connected to the slide, a control-member for said pawls movably journaled in the slide, and stop members adapted to operate said control-member in the end positions of the slide so as to bring the pawls in and out of engagement with the racks.
- 25 4. In a mechanical pencil, a step by step feeding mechanism for the lead or crayon, comprising a stationary and a slidable rack, means for reciprocating said slidable rack, a slide between said racks, pawls carried by said slide and normally engaging said racks, a pusher connected to the slide, a control rod movably journaled in the slide, springs carried by said control rod and adapted to operate the pawls, and stop members adapted to 30 operate said control rod in the end positions of the slide so as to bring the pawls in and out of engagement with the racks.
- 35 5. In a mechanical pencil, a step by step feeding mechanism for the lead or crayon, comprising a stationary and a slidable rack, means for reciprocating said slidable rack, a slide between said racks, pawls carried by said slide and normally engaging said racks, a pusher connected to the slide, a control rod movably journaled in the slide, springs carried by said control rod and adapted to operate the pawls, and stop members adapted to 40 operate said control rod in the end positions of the slide so as to bring the pawls in and out of engagement with the racks.
- 45 6. In a mechanical pencil, a step by step feeding mechanism for the lead or crayon, comprising a stationary and a slidable rack, means for reciprocating said slidable rack, a slide between said racks, pawls carried by said slide and normally engaging said racks, a pusher connected to the slide, a control rod movably journaled in the slide, springs carried by said control rod and adapted to operate the pawls, and stop members adapted to 45 operate said control rod in the end positions of the slide so as to bring the pawls in and out of engagement with the racks.

In testimony whereof I have signed my name.

EINAR GUSTAF EVALD HOGNER.
